United States Patent Office.

ROSCOE G. ELDER, OF NEW YORK, N. Y.

Letters Patent No. 102,927, dated May 10, 1870.

IMPROVEMENT IN CHILDREN'S CARRIAGES.

The Schedule referred to in these Letters Patent and making part of the same.

To all whom it may concern:

Be it known that I, ROSCOE G. ELDER, of the city, county and State of New York, have invented a new and useful Improvement in Children's Carriages; and I do hereby declare the following to be a full, clear, and exact description thereof, which will enable those skilled in the art to make and use the same, reference being had to the accompanying drawing forming a part of this specification, in which drawing—

Figure 1 represents a perspective view of this invention.

Figure 2 is a detached sectional view of the drop and front axle, in a larger scale than the previous figure.

Figure 3 is a detached end view of the same.

Similar letters indicate corresponding parts.

This invention consists in the arrangement of a drop or bearing for the front axle, formed beyond or below the end of the sill, and attached to said sill by means of a strap or cap, in such a manner, that by said drop the end of the sill is protected, and a neat and ornamental finish is given to it. The drop is only partially bored through to receive the end of the axle, which is drawn up tight by means of a screw tapped in its end in such a manner that the axle remains stationary, while the wheels revolve thereon and that by unscrewing the screws, the axle can be readily taken out of the drops without unfastening said drops from the sills.

In the drawing the letter A designates the front axle of a children's carriage which has its bearings in drops a, secured to the ends of the sills b. Said drops are formed beyond or below the ends of the sills, each drop being attached to its sill by means of a bracket, c, which covers the end of the sill, and which may be made to extend up at the under side of said sill, as shown in fig. 3 of the drawing. By these means the

end of the sill is protected by the drop, and when the drop is made in an ornamental form, it materially improves the appearance of the carriage.

Each drop is bored out to receive the end of the axle A, the hole or socket in the drop extending only partially through the same, as shown in fig. 2, so that a shoulder, d, is formed in the interior of the drop, against which the end of the axle can be drawn up tight by means of a screw, e, which is tapped into the axle and passes loosely through a hole in the drop. By this arrangement, the axle can be easily and firmly secured in the drop, and, by removing the screw e, the axle can be taken out without unscrewing the bracket c. By interposing one or more washers between the end of the axle and the shoulder d, the position of the axle can be accommodated to the length of the hub of the wheel, so that the wheel will run freely on the axle without binding. The screw e instead of being tapped into the end of the axle, may be made to bear on the side of the same in the manner of an ordinary set screw, so that the axle can be moved in and out, and retained in the desired position.

What I claim as new, and desire to secure by Letters Patent, is—

1. The arrangement of a drop, a, beyond, or below the end of the sill b of a children's carriage, so as to protect said end and impart to it an ornamental appearance, substantially as set forth.

2. The shoulder d in the interior of the drop a, in combination with the screw e and axle A, substantially as, and for the purpose herein shown and described.

This specification signed by me this 4th day of April, 1870.

ROSCOE G. ELDER.
